UNITED STATES PATENT OFFICE.

ALLEN HAMMOND WHISNER, OF GIBSONVILLE, NORTH CAROLINA.

NURSING-BOTTLE HOLDER.

Application filed February 20, 1923. Serial No. 620,225.

To all whom it may concern:

Be it known that I, ALLEN H. WHISNER, a citizen of the United States, residing at Gibsonville, in the county of Guilford and

5 State of North Carolina, have invented certain new and useful Improvements in Nursing-Bottle Holders, of which the following is a specification.

This invention relates to certain new and 10 useful improvements in holders for nursing bottles, and it has for its objects among others to provide a simple, cheap, yet efficient mechanical device by means of which the nursing bottle may be supported in such 15 position that the infant may conveniently nurse while lying upon its back, the device being such that it cannot easily be upset, may be folded up when not in use, and one in which the bottle when in use will be 20 securely held in an inclined position.

It has for a further object to adapt the holder to any style of nursing bottle, the bottle being easily inserted and removed, the holding members having sufficient resiliency 25 also to admit of some movement of the bottle in the hand of the infant, yet stiff enough to maintain their form and to retain the bottle.

Other objects and advantages of the invention will hereinafter appear and the 30 novel features thereof will be specifically defined by the appended claims.

The invention is clearly illustrated in the accompanying drawings, which, with the 35 numerals of reference marked thereon, form a part of this specification, and in which—

Figure 1 is an elevation of my improved holder as in use, the nursing bottle being shown in dotted lines.

40 Figure 2 is a top plan view of the holder.

Figure 3 is an enlarged perspective view of a portion of the body showing one of the spring clips.

Like numerals of reference indicate like 45 parts throughout the several views.

My holder in its preferred form is constructed preferably, although not necessarily, of coppered wire so as to be practically germ proof. In its preferred form it is 50 composed of three pieces hinged one to another, and each piece preferably made of a single piece of material.

Referring to the drawings,

55 1 designates one of such pieces which constitutes the body of the device, the said piece being folded upon itself and forming

a loop 2 at one end of such body, and a loop 3 at the other end, the portion between the loops being twisted, as shown. One end of the wire forming the body is bent downward through the loop 2 and inclined toward the other end, as seen at 4, and thence formed into a coil or preferably a plurality of coils 5, as seen best in Figure 1, which coils are adapted to receive and resiliently hold the 60 bottom end of the bottle 6, as indicated by dotted lines in Figure 1. The other end of the wire forming the body is extended downwardly through the loop 3 and in an inclined direction terminating in a coil 8 65 70 which is adapted to receive and hold the nipple end 9 of the bottle.

The inclined portion of the wire is seen at 7 in Figures 1 and 3. Intermediate the coil 8 and the loop 3 this end of the wire 75 forming the body is given an outward and under and upward curvature, as seen at 10, to engage the sides and bottom of the bottle, the coil 8 pressing upward against the nipple at the rim of the bottle, and all together holding the bottle securely in a 80 downwardly inclined position.

I provide the body with front and rear legs which are made substantially alike with the exception that the hind legs are longer 85 and the hind feet stand farther apart. The hind legs 11 comprise the spread-apart portions 12 formed by a single piece of wire, the ends of the wire being bent around the transverse portion of the loop 2, as seen at 90 13, so as to form a hinge, permitting the legs 11 to be folded beneath the body 1, as seen in dotted lines in Figure 1, when the device is not in use. The hind legs are provided with a return bend 14 between the feet 95 12, as seen clearly in Figure 2, which stiffens the device and adds to its safety.

The front legs are similar in all respects to the hind legs, having the feet 15 and the return bend 16 between such feet, as seen in 100 Figure 2, these legs being shorter and not spread so far apart as those of the hind legs.

At the joints between the legs and the loops at the ends of the body 1 the ends of 105 the wires forming the legs are extended, as seen at 17 and 18, so as to reach down over and straddle the top of the body, these ends being crossed, as seen best in Figure 2, and provided with depressions, as seen at 19 and 110 20, Figure 2, on their inner surfaces to hold the device with the legs securely held in

position, as seen in full lines in Figure 1. When not in use these spring snaps readily release their hold on the body 1, and as both the front and hind legs are alike jointed 5 to the body they both can be folded up beneath the body, as seen in dotted lines in Figure 1.

Figure 1 shows the device as in use. The front feet are designed to rest upon the 10 bed on either side of the child's neck, there being no pressure whatever upon the child; the hind legs rest upon the bed on either side of the child's limbs, and the bottle is held in an inclined position which may be 15 varied as desired, by raising or lowering the front or back coils. In addition to adding to the comfort of the child, it saves the busy mother many hours of valuable time.

The device provides a special safety feature 20 in the low bow over the child's limbs, which may be drawn back so that a garment may be laid over it to anchor it in position. In fact, a warm wrap may be laid over the 25 whole device in rough out-of-door conditions to keep the little hands and bottle warm, without in the least interfering with the child's nursing.

Modifications in detail may be resorted to without departing from the spirit of the 30 invention or sacrificing any of its advantages.

What I claim as new is:—

1. A nursing bottle holder comprising a

body portion, legs at opposite ends thereof and means movable with the legs and engageable with the body portion to hold the legs in extended position. 35

2. A nursing bottle holder comprising a body portion, legs at opposite ends thereof and means movable with the legs and engageable with the body portion to hold the legs in extended position, and bottle-holding means on the body portion. 40

3. A nursing bottle holder comprising a body portion with legs at opposite ends 45 thereof, the legs at one end being longer than those at the opposite end, means movable with the legs to engage and hold the body portion in fixed relation to the legs, and bottle-holding means on the body portion. 50

4. A nursing bottle holder comprising a body portion with a loop at each end, the ends of the material forming the body portion being extended through said loops and 55 formed into coils to receive and hold opposite ends of a bottle.

5. A nursing bottle holder comprising a body portion looped at its ends and having bottle receiving coils, and legs hingedly 60 connected with said loops and having their ends extended to form spring clamps to engage the body portion.

In testimony whereof I affix my signature.

ALLEN HAMMOND WHISNER.
